(57) **CLAIM**

I claim the ornamental design for a food identification device, as shown and described.

DESCRIPTION

FIG. 1 is a front perspective view of a food identification device showing my new design;

FIG. 2 is a rear perspective view thereof;

FIG. 3 is a top plan view thereof;

FIG. 4 is a front elevation view thereof;

FIG. 5 is a right side elevation view thereof;

FIG. 6 is a left side elevation view thereof;

FIG. 7 is a rear elevation view thereof; and,

FIG. 8 is a bottom plan view thereof.

In the drawings, the broken lines represent features of the food identification device which form no part of the claimed design.
